UNITED STATES PATENT OFFICE.

OTTO GRÜNEWALD, JR., OF NEW YORK, N. Y., AND GEORGE BASIL HOOPER,
OF NEWARK, NEW JERSEY, ASSIGNORS TO THE J. L. MOTT IRON WORKS,
OF NEW YORK, N. Y.

DESIGN FOR A DRINKING-FOUNTAIN.

SPECIFICATION forming part of Design No. 34,531, dated May 21, 1901.

Application filed April 26, 1901. Serial No. 57,629. Term of patent 14 years.

To all whom it may concern:

Be it known that we, OTTO GRÜNEWALD, Jr., residing in the borough of Bronx, city and State of New York, and GEORGE BASIL HOOPER, residing at Newark, in the county of Essex and State of New Jersey, citizens of the United States, have invented and produced a new and original Design for a Drinking-Fountain, of which the following is a specification, reference being had to the accompanying drawing, forming part thereof, in which we have represented our new and original design by an elevation.

As shown in the drawing, the leading or material features of our design consist of the ornamental configuration at the upper portion of the base, the ornamentation at the upper portion of the tapering shaft, the ornamental globe-supports on opposite sides of the shaft and the intermediate surface ornaments, and the ornamental shape and configuration of the surmounting lamp and its support.

The design of the base comprises the flat surfaces *a b c*, the molded edge 2, the panel 3, the molded girdle 4, the ornamental connected ellipse figures 5, the tapering molded surface 6, intermediate to the girdle and ellipse figure 5, the ornamental bows 7 and 8, the lion's-head medallion and leaf ornaments *d* in panel 10, the molded cornice 11, with arched centers 12, and the egg-and-dart ornament 13, above the panel 10, below the cornice 11, and in outline conforming to the cornice and the arched centers.

The design of the tapering shaft comprises a base 14, the rib-and-cove ornament 15, the plain tapering shaft *e* and the rib 17, the wreath-and-ribbon ornament 18, near the upper end of the shaft, the cornice 19, and the

acanthus-leaf molding 20, with an egg-and-dart molding 21 coming below the cornice 19 and at the upper end of the tapering shaft.

Branching out from opposite sides of the tapering shaft are the ornamental outward and upward curved arms 22, with foliated edges and leaf-and-scroll return ornaments, upon the ends of which are represented the globe-sockets 23 and lamp-staffs 24. Upon the face of the tapering shaft and intermediate to the curved arms 22 is a fleur-de-lis shield and medallion 34, with a scroll edge and leaf-and-ribbon ornament 25, and the tapering shaft is surmounted by a cap 26, with a flat upper surface.

The design of the surmounting lamp and its support comprises the inclined tapering legs 27, with claw-feet and crested upper ends merging into an ornamental union-band 28, with crown ornaments 29 above the band and in line with the legs 27. Within the boundary of the tapering legs is a base-band 29. The lamp-globe 30 is within the union-band 28, and it is surmounted by a dome-shaped cap 31 and provided with a cup-shaped base 32.

The surface of the panel 3 and surface of the greater portion of the tapering shaft *e* are plain.

Having described our invention, what we claim as new, and desire to secure by Letters Patent, is—

The design for a drinking-fountain, substantially as herein shown and described.

Signed by us this 23d day of April, 1901.

OTTO GRÜNEWALD, JR.
GEORGE BASIL HOOPER.
